UNITED STATES PATENT OFFICE.

EARL B. LEAR, OF PHILLIPSBURG, NEW JERSEY, ASSIGNOR TO INGERSOLL-RAND COMPANY, OF JERSEY CITY, NEW JERSEY, A CORPORATION OF NEW JERSEY.

DOUBLE-DRUM HOIST.

Application filed July 15, 1925. Serial No. 43,687.

To all whom it may concern:

Be it known that I, EARL B. LEAR, a citizen of the United States, and a resident of Phillipsburg, county of Warren, and State 5 of New Jersey, have invented a certain Double-Drum Hoist, of which the following is a specification accompanied by drawings.

This invention relates to hoists, but more particularly to a power driven hoist of the 10 double drum type.

The objects of this invention are to enable two drums as for instance, a haulage drum and a tail-rope drum, to be connected selectively with a common driving shaft.

Another object is to simplify the construction and to insure ease and certainty of operation in devices for automatically connecting one drum with a driving shaft and simultaneously disconnecting the other drum from 20 the driving shaft in accordance with the direction of rotation of the shaft.

Other objects will be in part pointed out hereinafter.

The invention consists of the combinations 25 of elements, features of construction, and arrangement of parts having the general mode of operation substantially as herein-after described and more particularly pointed out in the appended claims and illustrated in the accompanying drawing, in which—

Figure 1 is a longitudinal sectional elevation of the hoist taken on the line 1—1 of Figure 2 looking in the direction of the 35 arrows.

Figure 2 is a transverse sectional view taken on the line 2—2 of Figure 1 looking in the direction of the arrows, and

Figure 3 is an enlarged detail perspective view of the pawl.

Referring to the drawing, the base plate A upon which the hoist is supported is in this instance swivelly mounted on the bed plate B to enable the hoist to be rotatably 45 adjusted in any desired position about a vertical axis. Any suitable motor may be provided for the hoist and in this instance a fluid pressure motor is indicated, having a casing C mounted on the base plate A, one end of which casing is closed by a plate D. Fluid pressure, as for instance compressed air, is supplied to the motor through the suitable inlet (not shown) controlled by a suitable valve E in the valve chest F adapted 50 to be manipulated by the valve lever G. In

this instance, the motor is assumed to be a reversible motor, the reversal of which is controlled by the valve lever G.

A center bearing H shown in this instance as a tubular support in the form of a shell, 60 is supported at one end in the gear box J and is secured thereto by the center bearing retaining screw K which secures the center bearing to the inner wall of the gear box J. The gear box cover L is secured to the 65 gear box J by means of bolts O. The construction of the motor and frame so far described has a minimum of parts, is strong and compact, easily assembled and dis-assembled, and permits ready accessibility to the 70 operative parts of the hoist.

A driving shaft P passing longitudinally through the center bearing H is supported at one end in the anti-friction bearing Q and is connected to be rotated by the motor in 75 any suitable manner. A driving pinion R is preferably keyed to the driving shaft P and meshes with an intermediate gear S journaled on the counter shaft T mounted in the gear box J. The intermediate gear S 80 is provided with bearings U and V and an intermediate pinion W in this instance forms a portion of the intermediate gear S and meshes with an internal gear X of the main driver Y preferably 85 in the form of a hollow rotatable shaft adapted to rotate on the center bearing H. Power is taken from the main driver for driving either one of the two drums Z and a loosely mounted relative to the main driver Y and rotatable about the driving shaft P. It will thus be seen that the main driver Y is connected as by means of gearing to the main driving shaft P and one of the drums a is conveniently journaled on the 95 center bearing H.

The haulage drum a, to which one length of the cable b is adapted to be connected, rotates preferably upon a bushing c upon the center bearing H and the tail rope drum 100 Z which is in this instance mounted beside the drum a in line therewith and to which the tail rope d is connected, preferably rotates upon the main driver Y as a convenient and compact construction. Such construction 105 of the drums materially reduces the over-all length of the hoist and produces a compact and well balanced hoist. Although one of the drums is shown journaled on the center bearing and the other drum journaled 110

upon the main driver, it is to be understood that this construction is merely shown for illustrative purposes and as this arrangement forms no part of the present invention, 5 this invention is not limited to the construction shown except as defined by the appended claims.

Means are provided for automatically connecting the main driver Y to one or the 10 other of the drums Z and a in accordance with the direction of rotation of the driving shaft P and for this purpose the haulage drum a is provided with a driver having clutch members in the form of teeth e. The 15 teeth e are in this instance shown formed on a flange f of the drum a but it is to be understood that they may be formed on a member separate from the drum a if desired and suitably secured thereto. The tail 20 rope drum Z is likewise provided with a driver having clutch members in the form of teeth g formed on the drum flange h but facing in the opposite direction from the teeth e.

25 A pawl carrier in this instance comprises a pair of annular plates or idlers j and k which are adapted to rotate relative to the center bearing H. The idler j in this instance bears directly on the center bearing 30 H and the idler k in this instance bears on the main driver Y. Pins o hold the idlers j and k in separated relationship and a pawl p is in this instance pivotally mounted on one of the pins o. The pawl p is preferably 35 formed with opposed engaging surfaces q and r which are adapted to engage a tooth e or g on the drums a and Z respectively, in accordance with the direction of rotation of the driving shaft P and consequent rotation 40 of the main driver Y. Although but one pawl is shown on the drawing, it is to be understood that as many pawls as necessary may be used and each pawl is adapted to rock vertically about a pin o and when one 45 of the engaging surfaces q and r engage a tooth on one or the other of the drums, the opposite engaging surface is out of engagement. In this manner, when one drum is 50 being driven the other drum is free to rotate independently thereof.

In order to actuate the pawl p into engagement with the tooth on one or the other of the drum drivers, the pawl p is preferably provided with gear teeth s formed in 55 its underside to mesh with similar gear teeth t formed on an annular ring u. The ring u is preferably keyed to the main driver Y in order to rotate therewith, and a set screw v is screwed into the ring u and 60 bears against the driver Y to hold the two parts in fixed relationship.

In order to exert a braking or checking 65 effect on the center bearing H for holding the plate or idler k of the pawl carrier stationary momentarily, a recess w is formed

in the plate j and a friction shoe x having a guiding projection y bears against the center bearing H. The guiding projection y of the friction shoe x extends into an aperture z in the plate j and a coil spring 2, which 70 bears against the pin o at one end and against the projection y at the opposite end, forces the friction shoe x against the center bearing H.

In the operation of the hoist so far described, if it be assumed that the driving shaft P is being rotated in the direction of the arrow 3 in Figure 2, the main driver Y will be rotated through a train of gearing described in the direction of the arrow 4 80 in Figure 2 and the teeth t on the annular ring u will bear against the teeth s of the pawl p and positively move the pawl into engagement with one of the teeth e and thereby drive the drum a in a counter-clockwise direction. It will be seen that the entire driving power is transmitted directly from the teeth t of the ring u to the pawl p and the pawl carrier merely serves to carry the pawl and receives no part of the driving 90 thrust.

Upon reversal of the direction of the driving shaft P, the direction of rotation of the main driver Y will be reversed and the teeth t on the annular ring u will positively rock 95 the pawl p so that the engaging surface r will be rocked into engagement with the tooth g on the drum Z. The friction shoe x will hold the plates or idlers j and k of the pawl carrier stationary momentarily in 100 order to permit the teeth t to rock the pawl p into engagement with a tooth on one or the other of the drum drivers before the driving power is transmitted from the main driver to one or the other of the drums. 105 Whenever the direction of rotation of the driving shaft P is reversed, the pawl carrier is held stationary momentarily to permit the teeth t of the ring u to rock the pawl p into engagement with a tooth on one or the other 110 of the drums and thereafter the pawl carrier, pawl, annular ring u, together with the teeth t and s on the annular ring u and the pawl p respectively rotate as a unit about the driving shaft P. One drum or the other will 115 thus be automatically connected to the main driver Y from the driving shaft as often as the direction of rotation of the driving shaft is reversed.

The haulage drum a may be conveniently 120 provided with a flange 5 to which a brake band 6 is applied, being controlled by any suitable mechanical connection from a brake lever 7. The actual mechanical connection between the brake lever 7 and brake band 6 125 is not shown in the drawing as it forms no part of the present invention. Similarly, a brake band 8 is applied to a flange 9 on the tail rope drum Z and is suitably connected to be operated by a brake lever 10. 130

I claim:

1. In a hoist, the combination of a frame, a driving shaft, drums rotatable about said driving shaft, a motor connected for rotating said driving shaft, drivers on said drums, a main driver connected to be rotated by the driving shaft, an oscillating pawl associated with the main driver for automatically connecting said main driver with one or the other of said drums in accordance with the direction of rotation of the driving shaft, and positive means including longitudinal gear teeth independent of the opposed drivers for rocking said pawl through a plane transverse to the longitudinal axis of the hoist to engage one or the other of said drivers.
2. In a hoist, the combination of a frame, a driving shaft, a pair of drums rotatable about said driving shaft, a motor connected for rotating said driving shaft, opposed drivers carried by said drums respectively, a main driver connected to be rotated by the driving shaft, a pawl carrier rotatable about said driving shaft, a pawl pivoted to said carrier to rock through a transverse plane for automatically connecting said main driver with one or the other of said opposed

drivers in accordance with the direction of rotation of the driving shaft, a ring secured to said main driver, and longitudinal gear teeth on said ring to engage the pawl for rocking said pawl into engagement with one or the other of said opposed drivers.

3. In a hoist, the combination of a frame, a driving shaft, a pair of drums rotatable about said driving shaft, a motor connected to rotate the driving shaft, opposed drivers carried by said drums respectively, a main driver connected to be rotated by said driving shaft, a pawl carrier rotatable about said driving shaft, a pawl between the drums and pivoted on said carrier to rock through a transverse plane for automatically connecting the main driver with one or the other of said opposed drivers in accordance with the direction of rotation of the driving shaft, longitudinal gear teeth on said pawl, a ring on said main driver and rotatable therewith, and longitudinal gear teeth on said ring meshing with the teeth on the pawl for rocking said pawl into positive engagement with one or the other of said opposed drivers.

In testimony whereof I have signed this specification.

EARL B. LEAR.
